APPARATUS FOR EXPOSING LIGHT SENSITIVE PHOTOGRAPHIC FILM

Harold Lakin, San Mateo, Calif., assignor to Litton Pre-
cision Products, Inc., San Carlos, Calif., a corporation
of Delaware

Filed Sept. 20, 1965, Ser. No. 87,073

Term of patent 14 years

(Cl. D61—1)

Fig. 1.

*Fig. 2.**Fig. 3.*FIG. 1 is a front perspective view of an apparatus for exposing light sensitive photographic film, showing my new design;

FIG. 2 is a rear elevational view thereof; and

FIG. 3 is a rear elevational of the machine shown in FIG. 1 but showing a modified embodiment thereof wherein the exposed rear extension of the chassis is reduced in proportion to that seen in FIG. 2.

The left side of the machine, not shown, is substantially a mirror image of the right side seen in FIG. 1.

I claim:

The ornamental design for an apparatus for exposing light sensitive photographic film, substantially as shown and described.
